UNITED STATES PATENT OFFICE

2,278,837

INCANDESCENT LAMP

Adolphe de Castro, Los Angeles, Calif.

Application October 31, 1940, Serial No. 363,622

2 Claims.

(Cl. 176—26)

This invention relates to incandescent electric lamps of the kind having two or more filaments and has particular reference to the positioning of such filaments within the lamp.

An object of the invention is the placement of the filaments in the lamp in a manner to obtain a substantially centered light source when one or the other filament is, or both are, incandescent.

Another object of this invention is the prevention of incandescent electric lamps from turning black through use.

A further object is to secure for a spare or unused filament a higher degree of luminosity when it becomes automatically incandescent.

Still other objects will become apparent as the specification proceeds.

In the drawing:

Fig. 1 is a combination of a side elevation of a filament control device and a diagram of the wiring circuit of the lamp.

Fig. 2 is a perspective view of the control device shown in Fig. 1.

Fig. 3 is a front elevation of one form of the lamp, showing one arrangement of the filaments and indicating the filament control device in the base.

Fig. 4 is a top plan view of the lamp shown in Fig. 3.

Fig. 5 is a side elevation of the bulb and filament arrangement shown in Figs. 3 and 4, with a bayonet or pre-focus base substituted for the threaded type shown in Fig. 3.

Fig. 6 is a top plan view of a modified filament arrangement.

The invention herein described, although useful in many classes of multi-filament lamps, is particularly adaptable to the types disclosed in my Patents No. 1,758,434 and No. 1,538,372, and the invention will therefore be described in such embodiments.

In lamps of the latter class, a plurality of filaments are provided together with means whereby only one filament remains incandescent at a time, the burning out or rupturing of one filament acting to switch another filament into the circuit. In one such embodiment of my invention, two filaments and a control device are connected as indicated in Fig. 1. The conductor 1 is electrically connected to the fixed end of the thermostat element 2 and to the fixed end of resistance wire 3 by a rivet 4 or other suitable means passing through the wafer of non-conducting material 5. The resistance wire 3 is wound into a heating coil 6 surrounding the

thermostat element 2, and is connected to lead 7 which is joined at its other end to filament 8. When the thermostat element 2 is cool, the contact point 9, on the free end of the element, rests on contact point 10 fixed to the wafer 5 and electrically connected by means of wire 11 to filament 12. The other end of filaments 8 and 12 are both connected to the common return conductor 13. Conductor 1 is connected to the usual terminal 16 in the bottom of the base B of the lamp, as indicated in Fig. 3, and conductor 13 is connected to the base at 15.

When current is initially introduced through these wires, it will be obvious that filaments 8 and 12 are connected in parallel, the current to the latter filament passing through the thermostat element 2 and contacts 9 and 10. Heating coil 6, at all times in series with filament 8, soon heats thermostat element 2, causing it to rise from its rest position, lifting contact 9 from contact 10, thus breaking the circuit to filament 12. As the thermostat increases in temperature, it will continue to rise until it strikes the limiting stop 14.

When the current is turned off, the cooling thermostat element will gradually move toward its rest position where it will again close the circuit to filament 12. When filament 8 finally burns out, or in the event of its rupture or breakage, the circuit through the heating coil is of course broken, with the result that the thermostat drops in a few seconds and closes the circuit through filament 12. As current never again passes through the heating coil, contacts 9 and 10 now remain permanently closed. The limiting stop 14 serves to reduce the interval of time required for the second filament 12 to replace filament 8 as the illuminating means, as it limits the throw of the thermostat and thus reduces the arc through which it must travel until it closes the circuit to the spare filament.

By following the teachings of my Patent No. 1,758,434, the heating coil may be omitted if desired, and a thermostat element used that becomes sufficiently warm from the current that it conducts to open the contacts 9 and 10.

The present invention contemplates special filament arrangements for a two-fold purpose. The first of these has to do with a method of preventing the well-known blackening of the bulb from the continuous effect of the filament emissions, and the second is concerned with means whereby the two filaments have substantially the same optical centers. These two ends

may both be served by arrangements typified by those disclosed in the drawing.

In Fig. 4, both filaments are shown to have a coiled or sigmoidal form, and each is arranged in the general shape of the letter C. One filament is placed inside the C formed by the other, as indicated in Fig. 4, and both are disposed in substantially the same plane, as shown in Fig. 3. If these filaments are of the same thickness, it is necessary that they be of approximately the same total length in order properly to operate on the same voltage, and the convolutions or waves of the inner filament must therefore be either closer together or kinked into longer folds than the outside filament. The mid-sections of the filaments are supported on arms 16 embedded in the supporting cores E and e, and the ends are supported by conductors 8a and 8b, and 12a and 12b, each pair leading respectively to filaments 8 and 12.

Fig. 6 shows another suitable filament configuration to accomplish the purposes hereinbefore set forth. As in Fig. 4, both filaments have a C or crescent formation, but instead of one being placed totally within the arc of the other, they may have configurations of identical shape and size, but the openings in the crescents face in opposite directions and one end of each crescent is positioned inside the other. As in the configurations shown in Figs. 3 and 4, both filaments are disposed in substantially the same plane. The filament supporting structure will be obvious from an examination of Fig. 6.

In the filament arrangement shown in Figs. 3 and 4, the two filaments are physically substantially concentric, and they are therefore substantially concentric from an optical standpoint. This is true in any position of the lamp, as will be evident from an examination of Figs. 3, 4 and 5.

In Fig. 6, there is a slight displacement of the optical centers, but for most practical purposes the variation is negligible.

If a lamp of this type is examined before either filament has burned out, but after the first filament has been in use for a few hundred hours,

the spare filament will exhibit a coating not found on the first. This coating is not due to the relatively fresh condition of the filament, but rather to a collection or gathering of small particles emitted from the incandescent filament. These emanations, passing from the luminous to the dark filament, are indicated at F in Fig. 4. When there is not a second element in proximity to the incandescent filament, these emanations rise and darken whatever portion of the bulb is on top in the particular position in which the bulb happens to be oriented. A second filament, arranged in the bulb according to the teachings of this specification, gathers these minute particles thrown off from the incandescent filament, thus preventing the discoloration of the bulb. The coating thus acquired by the second filament also acts to produce a higher illumination when it finally comes into use than would otherwise be the case.

Many other suitable filament arrangements are possible within the broad scope of this invention, and it will be obvious to those skilled in the art that my invention may be embodied in sundry other forms, and that various substitutions may be made for the individual elements set forth in the claims without departing from the combinations covered thereby.

My claims are:

- 30 1. An incandescent lamp including a pair of filaments each having the general configuration of an incomplete circle, the open portions of the two configurations facing in substantially opposite directions with an end portion of one filament within the circle of the other; and a common conductor leading to each of said filaments.
- 35 2. An incandescent lamp including a pair of coiled filaments of many convolutions, each filament having a generally C-shaped configuration; one of said filaments disposed within the C formed by the other filament and having its convolutions so formed that the actual filament length is substantially the same as that of the outer filament; and a common conductor leading
- 40 45 to one terminal of each of said filaments.

ADOLPHE DE CASTRO.
